UNITED STATES PATENT OFFICE.

JOSEPH ALPHONSE DEMERS, OF ST. ROMUALD, QUEBEC, CANADA.

AUTOMATIC TRAIN SIGNALING, BRAKING, AND THROTTLE CUT-OFF.

1,149,251.

Specification of Letters Patent. Patented Aug. 10, 1915.

Application filed September 15, 1913. Serial No. 739,771.

To all whom it may concern:

Be it known that I, JOSEPH ALPHONSE DEMERS, a subject of the King of Great Britain, residing at St. Romuald, Province of Quebec, Canada, have invented certain new and useful Improvements in Automatic Train Signaling, Braking, and Throttle Cut-Offs; and I do hereby declare that the following is a full, clear, and exact description of the invention, such as will enable others skilled in the art to which it appertains to make and use the same.

The invention to be hereinafter described relates to railways, and more particularly to automatic mechanisms for signaling and applying the brakes at predetermined points.

Broadly speaking, the invention comprises means for signaling the engineer when the train reaches a predetermined point, means for applying the brakes, and means whereby the engineer can prevent the application of the brakes if he so desires.

In order to more clearly disclose the construction, operation, and use of the invention, reference should be had to the accompanying drawings forming part of the present application.

Throughout the several figures of the drawings like reference characters designate the same parts.

In the drawings: Figure 1 is a vertical sectional view through the casing showing the operating mechanism in elevation; with the brakes applied; Fig. 2 is a view of Fig. 1 taken from the right side, with the side of the casing removed; Fig. 3 is a section taken on line 3-3 of Fig. 4, looking in the direction of the arrows; Fig. 4 is a section taken on line 4-4 of Fig. 3, looking in the direction of the arrows; Fig. 5 is a side elevation of the device for operating the signal actuating lever; Fig. 6 is a side view of an engine and tender showing the device suspended from the tender and how it is operated; Fig. 7 is a rear view of a locomotive cab with the device applied; Fig. 8 is an end view of the device for operating the brake actuating lever; Fig. 9 is a side elevation of the same; Fig. 10 is an enlarged detail view showing the means for operating the throttle lever; Fig. 11 is a detail view of the connections with the throttle lever; Fig. 12 is a detail view of a modification of Fig. 11; Fig. 13 is an end view of the casing, showing the shields, applied; Fig. 14 is a

bottom plan view of the same. Fig. 15 is a sectional view on line 15-15 of Fig. 1 looking in the direction of the arrows; Fig. 16 is a fragmentary detail view showing the mounting of the plate for operating the valve in the branch air pipe; Fig. 17 is a detail view in front elevation of the sliding bolt and its tubular guide; and Fig. 18 is a detail back view of the slidable bar and its mounting.

The main objects of the invention are to provide a simple and efficient mechanism for automatically sounding the signal setting the brakes, and operating the throttle lever to cut off the supply of steam to the cylinders, as the train is passing a predetermined point in the track, and to accomplish these operations entirely independent of the engineer or any other person.

The whole actuating mechanism is contained in a casing or box 1 which may be conveniently suspended from straps of the tender box. Within this case or box 1 is slidably mounted a bar 2, provided with an integral laterally projecting arm 2' which projects through a slot in the side of the box and travels at a short distance above the track. This bar is guided in a suitable U-bracket or strap secured to the bottom of the casing. The rear end of bar 2 is pivotally connected to the lower end of a lever 100 fulcrumed in a bracket 101 and connected at its upper end by a link 102 to a second link 103 the lower end of which is pivotally mounted in a suitable plate secured to the bottom of the casing. The upper end of this second link is provided with a pin 3 which projects over the upper edge of a loosely mounted U shaped bracket 4 so as to control and limit the motion thereof. One end of the guide bracket 4 is pivotally secured to the lower end of a lever 5 pivotally mounted at its center on a horizontal arm 5^a secured to the side of the casing 1, and the bracket is provided at its outer end, on its lower edge, with an integral plate 14 projecting at right angles thereto through the side of the casing 1. The upper end of lever 5 is connected by a link 6 to the handle 7 of a valve in the compressed air pipe 8. Above this valve a branch pipe 9 is tapped into the pipe 8. The branch pipe 9 traverses the case 1 and passes out through the top thereof, at the back.

In the inner vertical portion of the branch pipe 9 is placed a valve 9^a which is operated

through a slotted handle 10 which is connected by the usual pin to a rectangular plate 11 loosely carried on the outer end of a bolt 104 slidably mounted in the guide bracket 4 so as to form therewith a transverse lever and having an offset end playing through a slot in the end wall of the casing and within the metal shield or cap 105 which covers the slot. Plate 11 is slidably mounted between the end of the casing 1 and a suitable bracket secured thereto, for guiding purposes.

When the plate 11 and the bolt 104 are in a raised position, as shown in solid lines in Figs. 3 and 4, the valve 9^a is closed; as is also the valve in the compressed air pipe 8. The inner end of the bolt 104 is held in a raised or lowered position by an inwardly arched leaf spring 18.

At a predetermined point in the track is placed a set of operating trips; comprising a vertical trip 15 adapted to engage the arm 2' of bar 2 and a vertical trip 16 normally adapted to engage the projecting plate 14 secured to the bottom edge of the U bracket 4. The vertical trip 16 is secured on the outer end of a shaft 17 mounted in two blocks 18 which are mounted on cushion springs 19 carried in the sides of a casing 20. Contained within the casing 20 are two tension springs 21 having their outer ends secured to the ends of the casing and their inner ends secured to an eye 22 integral with shaft 17. By this means the vertical trip 16 is free to give either sidewise or vertically if too great pressure be exerted upon it.

When the train reaches a point where a set of the trips are placed; the arm 2' of bar 2 will first engage the trip 15 which will force the pin 3 forward and downward. Pin 3 will engage and force the guide bracket 4 downward, also, to the position shown in dotted lines in Fig. 3. As the bolt 104 of the guide bracket 4 carries the plate 11, it is evident that by forcing down the guide bracket, the valve 9^a will be opened and the compressed air allowed to flow through the branch pipe 9. The branch pipe 9 is connected to a whistle 23 located in the cab of the engine; so that the engineer is notified as soon as the engine reaches a set of trips. In the position shown in dotted lines in Fig. 3; the projecting end 55 of plate 14 secured to guide bracket 4 will be engaged by the vertical trip 16. The vertical trip 16 will force the bolt 104 backward to the position shown in Fig. 1. This will force the lower end of the pivotally mounted lever 5 backward, thus revolving it on its pivot so as to swing its upper end downward and forward, and thus open the valve in the compressed air pipe 8, which is connected to the brakes; and in this way 60 apply the brakes after notifying the engi-

neer. If the engineer knows that the track is clear and does not want the train stopped, he can prevent the brakes from being applied by special means provided for that purpose. A small cylinder 24 provided with the usual piston head and piston rod 25 which projects through the top of case 1, is secured to one end thereof. Mounted on the upper end of the piston rod 25 is a yoke composed of an L member 26 and an arm 27. The lower end of the L member 26 is secured by means of a chain 28 to the guide bracket 4, at a point near the free end thereof. The outer end of arm 27 is connected to the upper end of a tension spring 29 the lower end of which is secured to the bottom of case 1 by an anchor screw 30. A pipe 31 is connected to the lower end of the cylinder 24 and connected to any suitable source of compressed air supply; as the tank 32. Interposed in the pipe 31 between the cylinder 24 and tank 32 is a three way valve 33 normally closed; placed within easy reach of the engineer. As soon as the engineer hears the signal, he can open the valve 33 so as to permit the compressed air to enter pipe 31, and thus enter the cylinder 24 from the bottom, so as to force the piston rod 25 upward. This operation lifts the guide bracket 4 and its bolt 104 from the position shown in dotted lines in Fig. 3, to the position shown in solid lines, as will be obvious. In this position the plate 14 secured to the bracket 4 will be raised high enough not to be engaged by the vertical trip 16; and the brake actuating mechanism will not be operated thereby; thus allowing the train to continue on its way. In order to permit the piston head in the cylinder 24 to be forced upward, the cylinder is provided with a port 34, through its top wall. After the vertical trip 16 is passed the three way valve 33 is turned so as to permit the air in the cylinder 24 which is under pressure to escape; so that when the arm 2' of bar 2 is again engaged by another trip 15 the bracket 4 and the elements connected thereto may be made to again assume the positions shown in dotted lines in Fig. 3. The bar 2 and arm 2' are held normally in operative position by means of a coil spring 106 having its opposite ends connected, respectively, to one end wall of the casing and to the upper end of lever 100.

Exhaust air escaping from the air brake system does not pass directly to the atmosphere. It enters a branch pipe 200 and is delivered into a cylinder 201 beneath a piston head 202 from which projects a piston rod 203 to the upper end of which is connected an arm 7' which travels with the piston rod. The cylinder wall is provided with a plurality of escape passages 204 arranged to be uncovered by the piston head 130

202 as it reaches its upper limit, thus permitting escape of the exhaust. A cord or rope 8' is connected to the lower end of this arm, passed over a pulley 9' and secured to 5 one arm of an elbow lever 10' which is pivoted to the throttle lever 11'. The other arm of the elbow lever is bent at an angle to engage the hand grip 12' of the spring pressed pawl 13' which coöperates with the 10 rack 14' to hold the throttle lever in its adjusted position. Thus, as the arm 7' travels outward with the piston rod 203, it will operate the elbow lever 10' and cause it to actuate the grip 12' to disengage the pawl 15 13' from the arc plate 14'. Continued movement of the arm 7' will move the throttle lever to cut off the steam to the cylinder. A somewhat simpler construction is shown in Fig. 12. Here the grip 12' has been formed 20 as a bell crank lever to one arm of which the cord 8' is attached, completely eliminating the elbow lever 10'. Thus, the supply of steam will be automatically cut off, in case the engineer has been incapacitated.

25 In order to shield arm 2' of the plate 2 and plate 14 of bracket 4 and prevent engagement of the same by any obstruction along the track, and to prevent entrance of snow to the interior of the casing, by way 30 of the slot and opening through which these parts operate, shields have been provided. These shields are both the same and therefore but one need be described. Each shield comprises a side plate 40 arranged at an 35 angle to the side of the casing and extending downwardly and outwardly from a point near the top of the casing to a point just below the bottom of the casing. The upper edge is hinged to the casing in any 40 suitable manner and a spring 41 acts to force the plate, normally, inward toward the adjacent casing wall. The triangular space between each inclined edge of the plate 40 and the casing wall is closed by a vertical 45 triangular wall 42. The bottom is closed by a triangular plate 43 having two oppositely inclined beveled or cam edges 44 and 45 each leaving a small triangular gap between its edge and the side of the casing. This 50 gap at its widest point, is just sufficient to receive the upper end of one of the trips 15 or 16 which, as the train travels forward, engages the cam edge and forces the shield outwardly until it engages and actuates the 55 plate 14 or the arm 2'. The shield then snaps shut again, the bottom 43 extending beneath the bottom of the casing. The cap 105, previously mentioned, keeps the slot of the bolt 104 closed weather proof.

60 It is thought that the construction, operation, and use of the invention will be clear from the preceding detailed description.

Changes may be made in the construction, arrangement, and disposition of the several 65 parts of the invention without in any way

departing from the field and scope of the same, and it is meant to include all such within this application wherein only a preferred form has been disclosed.

Having thus fully described my invention, what I claim as new and desire to secure by Letters Patent is:

1. In a device of the character described, a casing, a compressed air pipe partly in said casing, a valve in the pipe, a branch pipe connected to the compressed air pipe, a valve therein, means for opening the valve in the compressed air pipe, means for opening the valve in the branch pipe, and means for preventing the opening of the valve in the compressed air pipe.

2. In a device of the character described, a casing, a compressed air pipe partly contained therein, a valve in the said pipe and in the casing, a pivotally mounted lever connected thereto, a transverse lever pivotally connected to the lower end of the first mentioned lever, a pivotally mounted lever having an arm projecting from the casing and being adapted to limit and control the motion of the transverse lever, a branch pipe connected to the compressed air pipe, a valve therein and operated by the outer end of the transverse lever, a trip adapted to engage the projecting arm of the second mentioned pivotally mounted lever so as to force the transverse lever downwardly for signaling purposes, a plate secured to the transverse lever and projecting through the outer side of the casing, a trip adapted to engage the plate and force the lever back so as to open the valve in the compressed air pipe, means for holding the transverse lever in operative position, compressed air means for lifting the transverse lever out of operative position, and means for permitting the transverse lever to be again placed in operative position.

3. In a device of the character described, a casing, a compressed air pipe partly contained therein, a valve in the said pipe, a branch pipe connected to the compressed air pipe above the valve, a valve in the branch pipe, lever and trip means for opening the valve in the branch pipe, lever and trip means for opening the valve in the compressed air pipe, and means for preventing the opening of the valve in the compressed air pipe, comprising, a cylinder contained in the casing, a piston operative therein, a pipe connected to a source of compressed air supply and to the bottom of the cylinder, a yoke mounted on the upper end of the piston, a chain connecting one side of the yoke to the lever means for operating the valve in the branch pipe, a spring connection between the outer side of the yoke and the bottom of the casing, means for admitting compressed air to the pipe connected to the bottom of the cylinder, and means

for permitting the atmospheric air to be forced out of the cylinder.

4. In combination with a device of the character described, means for preventing the setting of the brakes comprising; a cylinder, a piston operative therein, a yoke mounted on the upper end of the piston rod, a compressed air pipe connected to the bottom of the cylinder and connected to a suitable source of supply, a three way valve interposed in the pipe, means for permitting the exhaust of atmospheric air from the cylinder as the piston is forced upward, and spring means for lowering the piston as the compressed air is permitted to escape from the cylinder.

5. In a device of the character described, a casing, a compressed air pipe partly in said casing, a valve in the pipe, a branch pipe connected to the compressed air pipe, a valve therein, means for opening the valve in the compressed air pipe, means for opening the valve in the branch pipe, means for preventing the opening of the valve in the compressed air pipe, a casing containing all said mechanism, a trip adapted to actuate said mechanism, and a shield movably connected to said casing and adapted to be engaged and actuated by said trip.

20 6. In a device of the character described, a casing, a compressed air pipe partly in said casing, a valve in the pipe, a branch pipe connected to the compressed air pipe,

a valve therein, means for opening the valve in the compressed air pipe, means for opening the valve in the branch pipe, means for preventing the opening of the valve in the compressed air pipe, a casing containing all said mechanism, a trip adapted to actuate said mechanism, a shield movably connected to said casing, and a cam plate carried by said shield and adapted to be engaged by said trip to actuate said shield.

7. In a device of the character described, a casing, a compressed air pipe partly in said casing, a valve in the pipe, a branch pipe connected to the compressed air pipe, a valve therein, means for opening the valve in the compressed air pipe, means for opening the valve in the branch pipe, means for preventing the opening of the valve in the compressed air pipe, a casing containing all said mechanism, a trip adapted to actuate said mechanism, a shield movably connected to said casing, a cam plate carried by said shield and adapted to be engaged by said trip to actuate said shield, and means for normally maintaining said shield in operative position.

In witness whereof I have hereunto set my hand in the presence of two witnesses.

JOSEPH ALPHONSE DEMERS.
